UNITED STATES PATENT OFFICE.

BENEDICT F. VOGT, OF LOUISVILLE, KENTUCKY.

REFRIGERATOR DRAWER.

Application filed September 4, 1924. Serial No. 735,798.

This invention relates to storage devices wherein drawers are employed for receiving articles to be stored in a compartment or casing. More especially the invention relates to a refrigerator such as is shown in my copending application for Patent No. 675,112, filed November 16, 1923, wherein a refrigerator is disclosed having refrigerating compartments for receiving food, certain of the compartments being provided with drawers for the reception of articles to be refrigerated.

In refrigerators it is common to place in the refrigerating compartments bottles, jars and other receptacles which are either open at the top or are so closed as to be liable to open when thrown down on one side. In my improved form of refrigerator in which drawers slide in and out of the refrigerating compartments these bottles and the like are placed on the bottom of the drawers and consequently the movement, in and out, of these drawers tends to upset such vessels.

The principal and most important object of the present invention is to provide a drawer for refrigerators and other storage compartments wherein a novel and improved arrangement will be made for holding bottles, jars, and other like receptacles in a vertical position, by means employed being adjustable both for use and disuse and for varying sizes of such receptacles.

A second important object of the invention is to provide a drawer of this description wherein means are used, formed from the sides of the drawer itself, for supporting the vessel retaining device in position for use.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a longitudinal vertical section 50 through a drawer provided with the vessel supporting device.

Figure 2 is an end view thereof.

Figure 3 is a section on the line 3—3 of Figure 1.

Figure 4 is a top plan view of one end of such a drawer.

Reference is had to my copending application, above referred to, wherein the location and use of drawers of this description is disclosed, the present application relating solely to the peculiar means of supporting vessels in the front and back of the drawer and to the formation of the drawer for supporting such means.

In this application a drawer has been shown peculiarly adapted for use in connection with refrigerating compartments. That is to say it is so arranged as to permit free circulation of air vertically through the drawer but it is to be understood that the device is applicable to other forms of drawers wherein it is not necessary that air circulate freely therethrough. However, in the present disclosure there is shown a drawer having side walls 10, a rear wall 11 and a front wall 12. The side walls 10 are turned in at the bottom to provide ledges 13 whereon rests a reticulated bottom 14 so that air may freely circulate through such drawer, also the side walls which are of metal preferably are provided with air circulating openings 15.

The drawer is preferably made of metal so that the side walls are formed of thin metal sheets and slightly above the middle of these side walls the metal is bent in to provide ledges 16. At one or both ends of these side walls, slightly above the ledges 16, there are provided openings 15 spaced from the end and also spaced slightly above the upper surface of the ledges 16. These openings 15 are disposed in oppositely positioned pairs for the reception of the journal ends 18 of substantially U-shaped bars each having a centrally straight portion 19 and legs 20. These bars are substantially resilient to permit the journal ends 18 to be sprung out of one set or pair of openings 15 and inserted in another. Moreover the first pair of openings, at each end of the drawer is sufficiently near to that end to allow the straight portion 19 of the bar to be folded close to the end, or to be folded away from the end, this portion and the adjacent parts of the legs 20 resting on the ledges 16 in each of said positions.

With this arrangement it will be obvious that a bottle, such as shown at B in Figure 1 may be held from falling over or a jar at J may be similarly held and that the bars 19 may be turned to lie close to the ends in position of disuse or away from the ends in

position of use. It will, furthermore, be noted that the spacing of these bars from the end may be varied by simply turning the bars from one position to the other on the journalled ends 18.

It will now be obvious that movement in and out of the drawers will not upset such bottles or vessels.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1: A drawer for the purpose described having side walls provided with oppositely disposed longitudinally extending ledges, and a U-shaped article retaining loop hav-

ings arms journalled in the side walls of said drawer and the said arms resting on said ledges.

2. A drawer for the purpose described having side walls each having an inwardly projecting longitudinally disposed ledge, the walls having opposed spaced openings adjacent one end and located above said ledge, and a U-shaped retaining bar having outwardly projecting ends engaging a pair of opposed openings in the side walls and resting on said ledge.

3. A drawer for the purpose described having side walls each having an inwardly projecting longitudinally disposed ledge, each wall having spaced openings adjacent one end and located above said ledge, and a U-shaped retaining bar having outwardly projecting ends engaging selectively in the openings in the said walls and resting on said ledge, said bar being movable in one position toward the end wall of the drawer and in the other position away from the same.

BENEDICT F. VOGT.
